CLAIM

The ornamental design for a display screen with animated graphical user interface, as shown and described.

DESCRIPTION

FIG. 1 is a front view a display screen with an animated graphical user interface, showing a first image of a first embodiment of the new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is a front view of a display screen with an animated graphical user interface, showing first image of a second embodiment the new design;

FIG. 9 is a second image thereof;

FIG. 10 is a third image thereof;

FIG. 11 is a fourth image thereof;

FIG. 12 is a fifth image thereof;

FIG. 13 is a sixth image thereof; and,

FIG. 14 is a seventh image thereof.

A first embodiment of the appearance of the animated user interface sequentially transitions between the images shown in the sequence of FIGS. 1-7. A second embodiment of the appearance of the animated user interface sequentially transitions between the images shown in the sequence of FIGS. 8-14. The process or period in which one image transitions to another image forms no part of the claimed design.

The broken lines showing the watch bands, the watch hands, and a numerical time are included for the purpose of illustrating environmental structure and form no part of the claimed design.

1 Claim, 14 Drawing Sheets
